(57) **CLAIM**

The ornamental design for an orifice part for flow cytometer
as shown and described.

DESCRIPTION

FIG. 1 is a front-upper-right side perspective view of an
orifice part for a flow cytometer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof, and

FIG. 7 is a bottom plan view thereof.

FIG. 8 is a cross-sectional view thereof cut along the lines
8-8 of FIG. 2; and,

FIG. 9 is a front-lower-right side perspective view showing
an example of the embodiment of FIG. 1.

The broken lines illustrating portions of the orifice part for
flow cytometer form no part of the claimed design. The
dot-dash broken lines defining the boundaries of the claimed
design form no part of the claimed design.
